Patented Oct. 24, 1916.

UNITED STATES PATENT OFFICE.

GEORGE H. ELKERTON, OF PORTLAND, OREGON.

VENT-PIPE FLASHING.

1,202,687.

Specification of Letters Patent. Patented Oct. 24, 1916.

Application filed November 24, 1913. Serial No. 802,594.

To all whom it may concern:

Be it known that I, GEORGE H. ELKERTON, a citizen of the United States, residing in the city of Portland, county of Multnomah, 5 and State of Oregon, have invented certain new and useful Improvements in Vent-Pipe Flashings, of which the following is a specification.

My invention relates to vent pipe flashings, and more particularly to certain improvements therein, whereby an absolutely water tight connection between the roof and a vent pipe is secured with a minimum amount of work and without any soldering 15 of joints after the device is adjusted in place.

Among the salient objects of the invention are,—to provide an improved vent pipe flashing device which can be made complete 20 in the shop and readily adapted to any angle of roof without any reconstruction thereof; to provide a device of the character referred to which is constructed in sections capable of being stacked together, one 25 within the other, as for shipment, or for carrying by hand, and which can be quickly separated and assembled without the use of tools; to provide in a device of the character referred to a construction in which 30 the projecting end of the vent pipe is completely covered, with a portion of the flashing device hooked over the upper end thereof, whereby to absolutely prevent water from running down the outside of 35 said pipe; and, in general, to provide a simple, efficient and practical vent pipe flashing of the character referred to.

In order that others may clearly understand my invention, I have shown on the 40 accompanying sheet of drawings, a vertical sectional view of one embodiment thereof, which I will now describe.

On the drawings, 1 designates a portion of a roof, shown in section, with a vent pipe 45 opening 2 therethrough to receive a vent pipe, as 3. Mounted upon the roof, over the opening therethrough, is a flashing sheet or plate 4, having secured thereto and as a part thereof a flashing base 5, terminating 50 in its upper portion in rounded part 5^a. Adjustably mounted upon said flashing base is a tubular member 6, terminating at its

lower end in an expanded and rounded portion 6^a adapted to fit snugly over the rounded part 5^a of the flashing base, and 55 to be adjustable thereupon, much as is a ball and socket joint, whereby to adapt it to any angle. Telescoping over the upper end of said tubular member 6 is a top tubular member 7, the upper end of which is 60 formed into an inturned hook-like form, in cross section, as shown, adapted to hook over the upper end of the vent pipe 3, whereby to prevent any water from finding its way upon or along the outside of said 65 vent pipe 3. The tubular members 6 and 7 are preferably slightly tapered, as indicated, whereby the member 7 can be telescoped bodily into the member 6, and the two members thus put together can be stuck through 70 the flashing plate or sheet 4 and its base 5, thus forming a package of small compass for shipment, or for convenience in packing. Any number of tubular members can be used, depending upon the distance to which 75 the vent pipe projects through the roof.

It will thus be seen that the device can be readily put in place upon a roof without any soldering or other fastening, other than to put the flashing plate or sheet 4 flat upon 80 the roof so that the shingles can be placed thereupon in the usual manner. The openings are large through the flashing plate and base, and the tubular members are slightly larger than the vent pipe, and inasmuch as the tubular members have a telescoping fit, they are readily adapted to vent 85 pipes of different lengths without being cut or reconstructed.

I do not limit the invention to this particular form except as I may be limited by the hereto appended claim, forming a part 90 hereof.

I claim,—

In combination with a roof and a straight 95 vent pipe extending therethrough, a flashing device therefor comprising a flashing sheet, or plate, adapted to said roof with an opening therethrough for said vent pipe, a flashing base secured over said opening 100 thereto and terminating at its upper end in a rounded portion, a tubular member adapted to fit over said vent pipe and terminating at its lower end in an expanded

rounded part, adapted to adjustably fit over the rounded portion of said flashing base, so as to be adjustable thereon to any angle relative to the vertical, and a second tubular member adapted to fit over said vent pipe and having a telescoping engagement at its lower end with the upper end of said first tubular member, and having its upper end turned inwardly and downwardly to hook

over and around the top of said vent pipe, 10 substantially as described.

Signed at Portland, Oregon, this 31st day of October, 1913.

GEORGE H. ELKERTON.

In presence of—

WARREN P. SMITH,
G. A. NICHOLS.
